INVENTOR,
Charles C. Hansen
BY Herbert G. Ogden
HIS ATTORNEYS.

UNITED STATES PATENT OFFICE.

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY.

DISK VALVE FOR ROCK DRILLS.

Application filed May 20, 1925. Serial No. 31,486.

This invention relates to fluid actuated rock drills, but more particularly to an improved distributing valve for such drills.

The objects of the invention are to simplify the construction of the valve and its parts, lighten the weight of the machine, and increase the drilling capacity.

Further objects of the invention will hereinafter appear and the invention is shown 10 in one of its preferred forms in the accompanying drawings, in which

Figure 1 is a longitudinal sectional elevation of so much of a rock drill as will serve to make the invention clear, and

15 Figure 2 is a detail longitudinal sectional plan view through the valve box on the lines 2-2 of Figure 1 looking in the direction of the arrows.

Referring to the drawings, the cylinder A and back head B are shown diagrammatically, and the piston C having the forward extension or shank D is preferably a hammer piston.

With the type of valve to which this invention relates the cylinder A is provided with a free exhaust port E controlled only by the piston, and the valve F controls only the inlet to each end of the cylinder through the inlet ports G and H. A valve chest 20 preferably located at the side of the cylinder comprises the block J having passages K and L and the cover O having a shallow circular recess P forming a valve chamber to receive the plate valve F in the form of a thin, flat circular oscillating disk having a 25 relatively broad, flat area. The cover O is formed with a flange O' forming a stop for the valve.

Pressure fluid is admitted from the supply Q and controlled by the usual throttle valve R and passes through the port S to the chamber of the valve box. The passages K and L connect the inlet ports T and U with the cylinder inlet ports G and H respectively.

The oscillating disk valve F in the valve box is held against rotation about its longitudinal axis by means of the pins V entering the notches W in the periphery of the valve. In the present instance the pins V also serve to locate the valve box with respect to the cylinder. The valve F is sub-

stantially uniformly tapered from its median line or diameter X towards the periphery at each side and in order that the valve shall freely oscillate without binding, suitable clearance is provided in the valve chest. The valve rests in direct contact with the valve seat along said median line to form a fulcrum. Sufficient clearance is also provided between the peripheries Y and Z of the valve and the valve chest to permit the live pressure fluid to pass over the ends of the valve to the cylinder.

In the operation of the device, let it be assumed that the piston is traveling on its rearward stroke as shown in Figure 1, with the valve in the position indicated, in which case live pressure fluid is passing from the supply Q to the valve chest and over the end Z of the valve and through the passage L to the forward end of the cylinder. As the piston moves rearwardly and uncovers the free exhaust port E pressure is reduced under the surface of the valve at the right hand side which is raised in Figure 1, while the opposite end of the valve is subjected to compression taking place in the rearward end of the cylinder, which causes the valve to oscillate and close the port U at the same time opening the opposite port T to supply live pressure fluid to the rearward end of the cylinder for driving the piston forward.

This improved valve operating on the current thrown principle is simple, compact, strong and efficient. The valve is made of sufficiently large diameter to provide large pressure surface and owing to its flat construction may be conveniently located at the side of the cylinder.

I claim:

A fluid actuated rock drill comprising a cylinder and reciprocating piston, a free exhaust port located centrally of the cylinder and controlled only by the piston, a valve box having a valve seat and a shallow circular bore forming a valve chamber located at the side of the cylinder, said valve box being formed with a flange forming a stop for the valve, a plate valve in the form of a thin flat oscillating circular disk having a relatively broad area in said box, said valve disk having clearance at opposite edge

portions and being uniformly tapered from its median diameter towards said opposite edge portions, the valve lying in direct contact with the valve seat along said median line to form a fulcrum, said valve having notches at the ends of its median diameter, pins entering said notches to hold the valve

against rotation about its longitudinal axis, and to locate the valve box with respect to the cylinder, and inlet ports for the cylinder controlled only by said valve. 10

In testimony whereof I have signed this specification.

CHARLES C. HANSEN.
